UNITED STATES PATENT OFFICE.

ALEX PETERSON, OF MINNEAPOLIS, MINNESOTA.

DESIGN FOR A PAPER-KNIFE.

44,934.

Specification for Design.

Patented Nov. 25, 1913.

Application filed May 7, 1913. Serial No. 766,193. Term of patent 7 years.

To all whom it may concern:

Be it known that I, ALEX PETERSON, a citizen of the United States, residing at Minneapolis, in the county of Hennepin and State of Minnesota, have invented a new, original, and ornamental Design for Paper-Knives, of which the following is a specification, reference being had to the accompanying drawing, forming a part thereof. The figure is a perspective view of the

paper knife, formed from an ordinary wire nail, showing my new design.

I claim:

The ornamental design for a paper knife, as shown.

ALEX PETERSON.
